N. B. HURD

DOOR LOCK AND LATCH

Filed Jan. 26, 1924

Patented Feb. 10, 1925.

UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR LOCK AND LATCH.

Application filed January 26, 1924. Serial No. 688,648.

To all whom it may concern:

Be it known that I, NORMAN B. HURD, a citizen of the United States of America, residing at New Britain, Connecticut, have invented new and useful Improvements in Door Locks and Latches, of which the following is a specification.

My invention relates to door locks and latches, and consists in providing a new form of dogging mechanism for the latch-bolt and stop-work, by which, when the door is closed and the stop-work is "on," both the latch and stop-work will be positively blocked against reversion from the outside, and yet said latch may be retracted by a key, for entrance from the outside, or by a knob on the inside of the door. In this instance the latch dogging means is of unique construction and operates in a novel manner. In this construction the stop-work cannot be thrown "off" by an unauthorized person, since it requires a preliminary movement of another part, preferably key-controlled, before the stop-work can be so moved. This is of great advantage because sometimes one in charge of a building, such as a school, may, at the closing hour, throw the stop-work on so that the door will be locked during the closed period. Anyone who happened to remain in the building, on going out, could carelessly or deliberately, reverse the ordinary stop-work so as to free the outer knob and thus leave the door unlocked. By my present construction the one in authority may throw the stop work "on" in the customary way, but when it is once "on," it cannot be thrown "off" excepting by the building attendant or someone in authority. It will be understood, of course, that the "stop-work" referred to is the means by which the outer knob or handle may be blocked against movement so that the latch cannot be retracted from the outside excepting by means of a suitable key. This being a very common way of locking a door instead of using a regulation "dead bolt."

In the accompanying drawings—

Fig. 1 is a side elevation of the lock and latch mechanism with the cap removed.

Fig. 2 is a front elevation.

Fig. 3 is a section on the line 3—3 of Fig. 1.

Fig. 4 is a section on the line 4—4 of Fig. 1.

Fig. 5 is a perspective view of one end of a detail.

1 represents the usual face plate through which protrudes a spring latch bolt 2. The usual case is connected to the rear of this face plate. 3—3^a are the plungers of the so-called "stop-work" by which the roll-back for the outside knob may be dogged so that the door cannot be opened from the outside excepting by means of a suitable key. 4 represents a roll-back for the outside knob. 5 represents a key-controlled roll-back ordinarily carried by a cylinder lock 6 at the outdoor side of the lock. 7 represents the tail of the latch bolt 2. 8 represents a coil spring mounted freely on the latch bolt tail and functioning to normally press the latch 2 outwardly. 9 represents a shoulder or abutment on the rear end of the tail 7. 10 is a latch retracting lever, pivoted at 11, one end of said lever bearing against the abutment 9 and the other end being adapted for engagement by the key roll-back 5. 12 is another latch retracting lever, pivoted at 13. 14 is a roll-back for operation by an indoor knob. This roll-back 14, as shown in Fig. 1, usually overlies the roll-back 4, which latter is controlled by the outdoor knob. I have not shown the ordinary inner and outer knobs and the corresponding spindles for coaction with the two roll-backs 4 and 14 since such details are very well known and require no illustration. The stop-work plungers are of the conventional type and the same are connected within the lock case by the usual walking-beam 15, so that, when one plunger is pushed in, the other will be pushed out. As shown in Fig. 1, the stop-work is in the "on" position, dogging the outer knob roll-back 4; that is to say, the rear end of the plunger 3^a has a nose 16 which projects into a recess on the hub of the roll-back 4, thereby preventing it from being turned. When the plunger 3 is pushed in, the plunger 3^a will be moved out, so that the tail 16 will be withdrawn from engagement with the roll-back 4, freeing the latter. 17 is a dogging lever, which functions to dog the latch bolt 2 and the stop-work plunger 3 when said lever stands in the position shown in solid lines in Fig. 1. This dogging lever 17 is pivoted at 18 and its lower edge rests upon a pin 19 on the latch-retracting lever 10. There is an incline on the lower edge of the 110

dogging lever 17, to the rear of the pin 19, so that, when the lever 10 is swung back it will quickly lift the dogging lever 17 to the dotted line position. It will be observed that the forward end of the dogging lever 17 is provided with two noses 20—21. When the stop-work is "on," as shown in Fig. 1, the nose 20 stands directly behind the upper end of the walking beam 15, so that the latter cannot be pushed back to throw the stop-work "off" and free the outer knob 22 is a lever, pivotally mounted at 23 on the latch bolt 2. 24 is a hooked nose on the outer end of the lever 22, the inner side of which is beveled to engage with the edge of the opening in the face plate through which it passes, so that, when the latch 2 is pushed back, as upon the closing of the door, the nose 24 will be cammed back by engagement with the face plate, the said lever 22 swinging from the position indicated in dotted lines in Fig. 3, to the position indicated in solid lines in said figure. 27 is what is termed a "box" strike plate, and it will be seen that when the door is fully closed the latch 2 and the nose 24 of the lever 22 will stand within the box-like opening of the strike plate. When the parts are in this position the inner end of the lever 22 will stand in front of the shoulder 21 on the end of the dogging lever 17 and thus it will be impossible to repress the latch by inserting a tool between the face plate 1 and the strike plate 27. It will likewise be impossible to manipulate the nose 24 by such method of attack, since that is positively held in the strike plate and cannot move to the dotted line position, in which position only, is the latch bolt free to be repressed. 26 is a bevel on the upper inner edge of the lever 22, and 26^a is a bevel on the end of the dogging lever 17, which bevel is in line with the bevel 26 when the lever 22 stands in the dotted line position shown in Fig. 3. When the door to which the lock is applied stands open, the lever 22 occupies this dotted line position, being held there under the influence of a suitable spring 25. 28 is a spring for the dogging lever 17, tending to normally depress the free end of the same. 29 is a spring for the latch retracting lever 12, and 30 is a detent spring to frictionally hold the stop-work in the "on" or "off" position.

Operation.—If a door to which the lock is applied stands open, and if the stop-work is "on", the parts would appear as shown in Fig. 1, in which position the nose 20 of the dogging lever 17 stands to the rear of the upper part of the walking beam 15, and hence the stop-work is positively blocked against being thrown off. Before the stop-work can be thrown off, it is necessary to insert a key in the cylinder lock 6 and turn the roll back 5 so as to move the latch retracting lever to the dotted line

position. This act will lift up the outer end of the dogging lever 17 until the nose 20 lines up with a notch 15^a in the rear edge of the walking beam 15. Obviously, the stop-work plunger 3 may now be pushed in to 70 throw "off" the stop-work and release the outer knob of the roll-back 4. This movement of the stop-work causes the walking beam 15 to move to the dotted line position, so that the shoulder 20 on the dogging 75 lever 17 will then stand in the notch 15^a and will be held elevated in this position until the stop work is again thrown "on". Manifestly, so long as the stop-work is "off", and the door is thereby unlocked, it is not so important that the latch 2 should be dogged, and therefore it is desirable to positively hold the dogging lever 17 in this elevated or "off" position, so that said latch bolt 2 may be freely retracted or repressed. If 85 the stop-work is "on" and the door is closed as shown in solid lines, Fig. 2, the latch 2 will, on the last part of the closing movement, encounter the strike plate 27. This will force the latch inwardly carrying with 90 it the lever 22. Before the incline on the outer end 24 of the lever encounters the face plate the rear beveled portion 26 will engage the co-acting beveled portion 26^a on the dogging lever, so that continued repression of 95 the latch 2 and lever 22 will operate to lift the free end of the dogging lever, whereby said latch and lever 22 may be fully repressed by the action of the strike plate. When the door is fully closed the latch 2 and the head 24 simultaneously spring forward and enter the box-like recess and occupy the position shown in Fig. 2. On the last end of the forward movement of the latch into the box strike, the rear end of 105 the lever 22 clears the forward end of the dogging lever 17, so that the latter will then drop down behind the lever 22 and operate as an abutment to dog the latch.

While I have shown my invention in a preferred form, I am aware that various changes may be made without departure from the spirit and scope of the invention as disclosed herein, and as covered by the following claims.

I claim:

1. In a door lock, a spring latch bolt, a dog therefor carried thereby and movable with respect thereto, a movable dogging abutment within the lock arranged to engage and disengage said dog, means carried by the lock to move said dog into its dogging position when the latch is retracted, co-acting means to be carried by the door casing for holding the dogging device in 120 its latch-dogging position when the door is closed and the latch is projected, and means to shift the dogging abutment within the lock to permit the latch to be withdrawn to unlock the door.

2. In a door lock, a spring latch bolt, a dog therefor carried thereby and movable thereon to a dogging and non-dogging position, means on the lock co-acting with the dog to move the same to the dogging position when the latch is retracted, means to be carried on the door casing to hold the dog in said dogging position when the latch is projected, a movable dogging abutment 5 times, stop-work mechanism operable in one 35 position to hold the outer hand operated roll-back against movement, means to dog the stop-work in said holding position while the door is open as well as closed, with means separate from said stop-work for 40 releasing the stop-work dogging means to permit said stop-work to be manually thrown off to release said outer hand operated roll-back.
- 10 5. In a door lock, a latch, an inside and an outside roll-back for independent hand operation for retracting the latch, a key-controlled roll-back for the outdoor side of the lock operable to retract said latch at all 45 times, stop-work mechanism operable in one 50 position to hold the outer hand operated roll-back against movement, means to dog the stop-work in said holding position, with means independent of the stop-work for releasing the stop-work dogging means to permit said stop-work to be thrown off to release said outer hand operated roll-back, a 55 dogging device carried by the latch bolt and co-acting with the stop-work dogging means when the stop-work is in its roll-back 60 holding position whereby said latch bolt will be held against retraction until its dog is released, said key-controlled roll-back when turned operating to first move the stop-work dog out of its latch dogging position and to then operating to retract the latch and permit the door to be opened. 65
- 15 3. In a door lock, a spring latch bolt, means at the indoor side of the lock to permit the latch bolt to be retracted thereby at all times, two separate means at the outdoor 20 side of said lock, one of the latter being key-controlled and arranged to retract the latch at all times, a movable stop-work for the other outdoor latch retracting means whereby the latter may be dogged at will, 25 with means co-acting with said stop-work to hold the same against being released from its dogging position excepting through the medium of a preliminary operation by said key-controlled means.
- 30 4. In a door lock, a latch, an inside and an outside roll-back for independent hand operation for retracting the latch, a key-controlled roll-back for the outdoor side of the lock operable to retract said latch at all

NORMAN B. HURD.
